(57) **CLAIM**

The ornamental design for a skateboard carabiner tool, as
shown and described.

DESCRIPTION

FIG. 1 is a perspective view of a skateboard tool showing my
new design with a closed key chain clip connected to the
bottle opener;

FIG. 2 is a perspective view of a skateboard tool showing the
key chain clip in an open position with the bottle opener
exposed;

FIG. 3 is a right plain view thereof showing the insert slot
for the Phillips screw driver and Allen wrench tool;

FIG. 4 is a left plain view thereof;

FIG. 5 is a front elevation view thereof;

FIG. 6 is a rear elevation view thereof;

FIG. 7 is a top elevation view thereof; and,

FIG. 8 is a bottom elevation view thereof looking down on
the graphite file.
